ERNEST C. EVERETT, OF NEW YORK, N. Y., ASSIGNOR TO R. E. DIETZ COMPANY, OF NEW YORK, N. Y.

BAIL-HOLDING DEVICE FOR LANTERNS.

1,353,991.

Specification of Letters Patent. Patented Sept. 28, 1920.

Application filed May 8, 1919. Serial No. 295,662.

To all whom it may concern:

Be it known that I, ERNEST C. EVERETT, a citizen of the United States, residing at New York city, in the county of New York and State of New York, have invented a new and useful Improvement in Bail-Holding Devices for Lanterns, of which the following is a specification.

This invention relates to improvements in lanterns and more particularly to a device for use on railroad lanterns for releasably holding the carrying bail rigidly in its upright position so that the lantern can be manipulated or moved to various positions by means of the bail without swinging on the bail.

In lanterns of the type commonly known as "railroad lanterns," the globe is surrounded by a frame or guard extending upwardly from the base portion of the lantern, and the top or upper portion of the lantern is hinged to the upper end of this guard or frame to swing to and from its normal position over the globe, so as to afford access to the globe and burner and permit the removal of the globe.

The object of the invention is to provide the movable top or upper portion of lanterns of this sort with one or more catches or devices of simple and inexpensive, but strong and durable construction, for releasably holding the bail rigidly in its upright position, the holding device or devices preferably being arranged and constructed so that it or they is or are moved into and out of holding engagement with the bail by the closing and opening of the hinged top of the lantern.

In the accompanying drawings:

0 Figure 1 is a front elevation of the upper portion of a lantern provided with bail holding means embodying the invention.

Fig. 2 is a plan view partly in section thereof.

5 Fig. 3 is a fragmentary front view showing the hinged top raised.

Fig. 4 is a fragmentary side view of the same.

Fig. 5 is an enlarged sectional plan on line 5—5, Fig. 1, showing one of the holding devices.

The lantern shown in the drawings, as is common in railroad lanterns, comprises a frame or guard A which extends upwardly from the lantern base, surrounding and pro-

tecting the globe B; and a top or upper portion C which is hinged in any suitable manner at one side, at c, to the upper portion of the frame or guard A so that the top can be swung to and from its operative position over the globe, with the chimney D, carried by the top, in engagement with the upper end of the globe. As usual, the hinged top C is provided with a suitable catch E adapted to engage the frame or guard for securing the hinged top in operative position. The catch shown consists of a spring wire secured to the underside of the hinged top and having a depending finger-piece adapted to spring into engagement with the top wire of the guard or frame and to be released by pressure on the finger-piece. F represents the carrying bail, the legs of which are hinged at f at their lower ends in any suitable way to the opposite sides of the lantern frame or guard so that the bail can swing up and down, to and from the upright carrying position, thus permitting the bail to be turned down at one side of the lantern for convenience in packing.

As thus far described the lantern is of common construction and may be constructed as shown or of other suitable or usual construction.

10 represents a catch or holding device on the hinged top C at one side thereof and adapted to engage the adjacent leg of the carrying bail F for releasably holding the bail in its upright position. Preferably two of these catches or holding devices are employed, located at the opposite sides of the lantern for engaging both legs of the bail in order to insure a stronger and more rigid construction, but either one or two of the catches or holding devices can be employed, as may be desired. The bail-holding devices 10 are rigidly or immovably secured or formed on the hinged top and each has a forked or slotted portion which extends toward and is adapted to straddle the adjacent leg of the carrying bail to hold the bail in upright position. Preferably each of the holding devices consists of a stiff wire which is bent around the air tube 11 of the lantern frame and is soldered or otherwise rigidly secured thereto, with the two ends 12 of the wire spaced and projecting out from the edge of the hinged top so as to straddle the leg of the bail. The leg of the carrying bail is provided with an out-

ward or lateral bend 13 above the point where the holding device engages the leg, this bend extending outwardly to a point laterally beyond the ends of the holding device, so that by raising the hinged top C until the holding device 10 is opposite the bend 13 of the leg, the bail is freed and can then be swung past the holding device to, and from its upright position. In order to 10 secure the bail, the hinged top is released and raised to the position indicated in Figs. 3 and 4, and the bail is then swung up until its legs are opposite the slots of the holding devices, and the hinged top is then closed 15 and secured, the closing movement of the top moving the forked or slotted ends of the holding device downwardly so as to straddle the legs of the bail below the bends 13 thereof. The bail is released by raising 20 the top until the holding devices register with the spaces formed by the bends 13 of the bail and the bail can then be swung downwardly. Thus by the simple and easy manipulation of the hinged top and bail, 25 the bail can be engaged with and disengaged from the holding devices which are rigid on the top. It will thus be apparent that holding devices rigid with the top and adapted to straddle or engage the legs of the bail 30 can be constructed and rigidly secured or formed on the top in various different ways.

The construction described forms a very rigid and sure holding means for the bail and the lantern can be carried and held by 35 the bail and moved to various positions for signaling or other purposes without danger of the holding devices being disengaged from the bail, loosened or broken by the manipulation of the lantern. The construction 40 is thus very much more rigid, reliable and durable than constructions in which the catch for the bail is hinged or movably mounted on the lantern top and is engaged with and disengaged from the bail by swinging or moving the catch or holding device. 45 Nevertheless the construction described is very simple and inexpensive.

I claim as my invention:

1. A lantern having a movable top, and a 50 movable carrying bail, said top and bail being provided with coöperating parts rigid

with said top and bail respectively and arranged to engage each other in the normal position of the top to hold the bail from movement, said parts being so arranged that 55 they are moved into and out of engagement with each other by relative movements of said top and bail.

2. In a lantern having a hinged upper frame portion which is movable to and from 60 its normal position, and a pivoted bail, a part which is rigid with said hinged frame portion and is arranged to engage said bail and hold it upright when said hinged frame portion is in its normal position, said bail 65 being so shaped that the movement of said hinged frame portion out of its normal position disengages said rigid part from the bail.

3. In a lantern having an upper frame 70 portion which is movable to and from its normal position, and a movable bail, a slotted part which is rigid with said movable frame portion of the lantern and is arranged, to straddle a leg of said bail and hold the 7 bail upright when said upper portion of the lantern is in its normal position, said bail being so shaped that it is freed from said part by moving said upper portion of the lantern out of normal position.

4. In a lantern having a hinged top, and a pivoted carrying bail, a part which is rigid with said top and is arranged to engage said bail and hold it upright, said bail having a portion extending outwardly laterally beyond said part, and said part being engaged with and disengaged from said bail by moving said hinged top.

5. In a lantern having a hinged top, and a pivoted carrying bail, a bail-holding device consisting of a bent wire embracing a part of said top and rigidly secured thereto and having spaced ends arranged to straddle a leg of said bail and hold the bail upright, said bail being freed from said holding device by moving said hinged top.

Witness my hand, this 2nd day of May, 1919.

ERNEST C. EVERETT.
